[57] ABSTRACT

Separate wall plates disposed perpendicularly to one another and with a seal between the abutting surfaces of the wall plates, form the mold cavity in a continuous casting mold. Each wall plate has a device for oscillating it in the radial direction of the mold cavity and another device for oscillating it in the plane of its contacting surface with the casting passing through the mold cavity. The wall plates are enclosed by a frame with abutment strips extending between the frame and the outer surface of the plates. Further, elastic elements are articulated to and extend between the wall plates and the frame. The elastic elements are adjustable for adapting to the tapering action of the casting as it moves through the mold.

OSCILLATING WALL ARRANGEMENT FOR A CONTINUOUS CASTING MOLD

SUMMARY OF THE INVENTION

The present invention is directed to the arrangement of a continuous casting mold for metal, and especially for steel, and, more particularly, it concerns separate wall members assembled together to form a mold cavity and with means associated with the wall members for oscillating them in two different directions.

In the past casting molds having walls oscillatable in two directions have only been feasible for casting copper. Other metallic materials, and in particular steel, whose thermal conductivity is lower than copper could not be cast in such molds. Because of its high conductivity, copper as the melt in a continuous casting arrangement causes less difficulty than does steel. In the prior art it has been realized that independently oscillatable walls disadvantageously limit the cooling rate because the walls defining the mold cavity do not remain in uninterrupted contact with the continuous casting. In an attempt to solve the problem, the amplitude of the vibrations or oscillations has been decreased from top to bottom in a vertically arranged mold. In such an arrangement the mold halves are pivotally mounted at their lower ends on horizontal shafts. In this known arrangement the mold surfaces pivot perpendicularly to the continuous casting and, while offering some improvement, the casting formed in such a device have not been completely free from cracks. It has been found that a sliding action occurs between the mold and the continuous casting which causes tensile stresses in the casting.

Further, when the mold surfaces pivot perpendicularly to the casting, the casting is exposed to relatively hard blows from the surfaces of the mold and such blows may easily develop surface defects in the castings.

Accordingly, it has been proposed to oscillate the mold surfaces in a circular or other closed orbit so that the surfaces move in the casting direction in contact with the casting and then become separated from the casting and return in the direction opposite to the casting direction to complete the orbit before returning into contact with the casting. As a result, the casting is contacted by the surfaces of the mold only while the surfaces are moving in the same direction as the casting.

However, because of the liquid characteristic of the material being cast as it enters into the mold cavity the manner of effecting this orbital movement of the mold surfaces is difficult without disadvantageously effecting the portion of the casting which is in the liquid state.

In one known device two bisected, matching mold parts which form the mold cavity are secured by means of bearings on eccentrically arranged shafts. As the shafts rotate a continual back-and-forth motion is imparted to the mold perpendicular to the casting direction.

When the above-mentioned device was used for continuously casting steel it was found impractical because it was incapable of removing the higher heat content of the steel in a sufficiently rapid manner. Since the mold surfaces are moved away from the surfaces of the casting during each radial movement of the mold, a time

interval exists during each cycle when no heat is being extracted from the casting.

When the continuous casting mold is oscillated in the casting direction, the heat transfer is suitable for a greater quantity of heat per unit of time. However, in such as arrangement the shell of the casting is stressed due to the oscillating action and surface defects occur at periodic intervals of time, for example, due to the velocity of the oscillating movement defects may form on the surface of the casting which make it unsuitable for further processing. In vertical casting arrangement, depending on whether the mean mold velocity downward is greater or less than the casting velocity, the movement is termed "negative strip" or "positive strip." It is possible for the upward and downward movement of the mold to take place at uniform speeds or the upward movement can be at a greater speed than the downward movement or vice versa. To provide such a movement in a specific case requires considerable expense in equipment to produce the exact movement of the mold in the casting direction, since not only the mold but the mold table must also be moved upwardly and downwardly. Moreover, in the case of curved continuous casting molds, the accuracy of the movement and the design of the required device is still more complicated than for vertically arranged molds due to the arcuate character of the movement. In curved mold arrangements a wearing action takes place on the mold walls due to the relative movement between the casting and the mold surfaces.

Therefore, in view of the problems involved in continuous casting arrangements where the wall surfaces of the mold perform a radial movement, it is the primary object of the present invention to provide a mold construction which overcomes the previously experienced problems and one that can be used for metals other than copper, and in particular for the casting of various types of steel. By means of the present invention, a better heat transfer is provided between the mold surfaces and the casting, so that metals of extremely high heat content can form an adequate casting shell and easily separate from the mold surfaces.

Therefore, in accordance with the present invention, separate wall plates are arranged for forming the mold cavity in a continuous casting mold and the wall plates are arranged for additional oscillating movement in the plane of the surface of contact between the wall plates and the casting within the mold cavity. With the combination of the oscillatory movement proposed by the invention and the conventional radially directed oscillatory movement, it is possible to effect the separation of the casting shell from the wall plates forming the mold cavity at a cost of energy and material which is as low as possible, and also to support the casting shell while avoiding the development of any tensile stresses. Furthermore, improved heat transfer is possible by means of the laterally directed displacements of the wall plates, so that the previously employed radially directed oscillatory movement is necessary only to insure better mixing of the liquid components within the casting and this feature also affords an acceleration of the heat removal from the interior or core of the casting into its outer zones. The different oscillatory movements of the wall plates thus cause sound or ultrasound waves to impinge upon the contents within the mold cavity, that is acting upon the internal structure of the casting and at the same time promoting the separa-

ration of the casting shell from the abutting surfaces of the wall plates.

Additional features can be incorporated into the casting mold assembly for improving its operation in accordance with the present invention. The individual wall plates are positioned inwardly from an enclosing and longitudinally extending frame and adjustable abutment strips extend between the frame and the wall plates providing support for the wall plates. These abutment strips or spacers and also the wall plates are exchangeable, so that the cross section of the mold cavity can be varied at a relatively small cost. Accordingly, the frame enclosing the exterior of the casting mold assembly acts as the basis for a system of exchangeable parts with the formation of variable cross-sections for the mold cavity based on the cross-sectional area provided within the frame.

Another feature of the invention is the provision of at least one device for generating oscillations being associated with each of the wall plates, such a device can be driven magnetically or by an electric motor. With this arrangement a much simpler oscillating means is provided, since lever elements and a plurality of bearing points are no longer needed. The alignment of such lever elements and bearing points has caused difficulty in previous oscillating devices and their use was considered to be disadvantageous because of the wear which developed and the generally heavy burden they imposed on the casting plant. Another feature of the present arrangement which is especially favorable is the synchronous operation of the oscillating devices for the pairs of oppositely arranged wall plates. By synchronizing the oscillations of the wall plates it is possible to maintain the necessary support for the casting shell as it moves through the mold cavity. By synchronizing opposed pairs of plates the oscillations in one direction for a pair of wall plates can be staggered with the oscillations of another pair of wall plates.

Still another feature of the invention which greatly facilitates the oscillatory action, is the use of elastic elements for supporting the individual wall plates on the frame. By employing adjustable elastic elements the disposition of the wall plates can be accommodated to the inwardly tapering action of the solidifying casting as it moves through the mold cavity. Because of the construction of the mold, butt joints are formed between the separate wall plates through which molten casting metal could flow under unfavorable conditions, however, since even a burr or similar defect on the surface of the casting is undesirable, it is important to arrange the abutting portions of the wall plates with a packing strip exposed to the pressure of a heat-resistant lubricant therebetween to afford the desired seal for the joint. In this way the lubricant fills any gap or space formed between the abutting portions. The lubricant reduces the friction between the abutting walls plates of the mold and also between the casting and the surfaces of the mold during the oscillatory movement of the mold parts, the lubricant enters the mold cavity only when a space occurs within the cavity. Since the packing strip is under pressure from the lubricant, it prevents the lubricant from flowing outwardly from the joint between the wall plates. Accordingly, the problem of providing a seal between the wall plates is overcome in an extremely simple manner.

The various features of novelty which characterize the invention are pointed out with particularity in the

claims annexed to and forming a part of this disclosure. For a better understanding of the invention, its operating advantages and specific objects attained by its use, reference should be had to the accompanying drawings and descriptive matter in which there is illustrated and described a preferred embodiment of the invention.

BRIEF DESCRIPTION OF THE DRAWING

In the drawing:

FIG. 1 is a plan view of a continuous casting mold assembly constructed in accordance with the present invention;

FIG. 2 is a vertical axial section taken along the line A—A in FIG. 1;

FIG. 3 is a partial vertical section similar to FIG. 2, however, viewed from the side in relation to FIG. 2; and

FIG. 4 is an enlarged, partial, horizontal sectional view of the butt joint between two adjacent wall plates of the continuous casting mold as indicated in FIG. 2, and viewed downwardly as in FIG. 1.

DETAILED DESCRIPTION OF THE INVENTION

In FIG. 1, a continuous casting mold assembly is shown with the mold cavity 1 formed by four wall plates 2, so that the mold cavity has a square transverse cross section. The wall plates 2 extend perpendicularly to one another with one end edge of each plate being in contact with the face surface of another plate and its opposite end edge extending outwardly from the free surface of the oppositely disposed wall plate. The metal being cast is charged downwardly into the mold cavity 1 with the casting being formed as it passes downwardly through the mold. Due to the pressure exerted by the casting metal against the wall plates 2, they are forced outwardly against abutment strips or members 3 which are located at the upper and lower ends of the plates and extend in planes transverse to the vertical axis of the mold cavity. Encircling the wall plates 2 and the abutment strips 3 is a closed frame 4 which extends in the longitudinal direction of the mold cavity for the height of the wall plates. Based on the desired cross sectional area of the mold cavity 1, the abutment strips 3 have special shapes or dimensions for providing the desired dimensions for the mold cavity 1. For effecting the radially directed oscillatory movement of the wall plates, they are supported on their outer surfaces by elastic elements 5 which extend outwardly and are secured in an articulated manner to the frame 4. As indicated in the drawing, two pairs of elastic elements 5 support the wall plates 2 from the frame 4, however, a greater number of such elastic elements can be used depending on the conditions involved. Such elastic elements 5 may be formed of SCHWING-METALLEN (registered trademark), that is oscillating metals, spring packages or compressed air cylinders and as such provide assemblies which are quickly installable and removable.

By means of the elastic elements 5, the wall plates 2 can be adjusted to accommodate the tapered configuration of the solidifying casting as it passes downwardly through the mold cavity. Alternatively, the elastic elements may be constructed so that they adapt automatically to the tapered configuration of the casting. As indicated in FIGS. 1 and 2, each of the wall plates 2 acts as a carrier or support for oscillation device 6 and the wall plate forms a unit with the device. As the oscillat-

ing device 6, an energy transmitter may be used which releases a sound wave into the material being cast so that its crystallization, during the solidifying action, can be favorably influenced.

Additionally, the oscillating devices 6 also serve for the equalization of the oscillating movements which are brought about by the essential component of the continuous casting mold in accordance with the invention. Further, as distinguished from devices used in the past, additional oscillating devices 7 are provided extending between one vertically extending edge of the wall plates 2 and the oppositely disposed surface of the frame 4. As indicated in the drawing, the oscillating devices 7 incorporate elastic elements so that a minimum of energy is expended in effecting the movement of the wall plates in planes perpendicular to one another, that is, in the planes of their surface in contact with the shell of the casting passing through the mold cavity. The present invention is directed especially to the combined oscillatory movements provided by the devices 6 and 7 so that each wall plate has, in combination, a radially directed oscillating movement and another oscillating movement in the direction of the surface or interface 8 between the casting shell and the contacting face of the wall plates 2. By oscillating the surface of the wall plates relative to the outer surface of the casting shell, the desired support for the casting surface is maintained.

As indicated in FIG. 2, the lower ends of the wall plates 2 are mounted on rolls 9 for supporting the weight of the mold. Further, as indicated above, and as shown in FIG. 2, the elastic elements 5 are articulated at their points of attachment 10 to the wall plates 2 and at their points of attachment 11 to the frame 4 for affording the relative displacement which occurs during the oscillatory movement of the wall plates.

In FIG. 4, the joint between a pair of wall plates is indicated with a groove formed in the edge of the wall plate which contacts the surface of the adjacent wall plate. A lubricant conduit 12 extends through the groove and is connected to a pressure reservoir, not shown. Within the groove, in the part spaced outwardly from the mold cavity 1, a packing strip is arranged so that it is forced into contact with the face 14 by the heat-resistant lubricant supplied into the groove through the conduit 12. By means of the heat-resistant lubricant and the packing strip 13, a seal is provided between the abutting surfaces of the wall plates 2 and, further, a lubricating action is provided between the wall plates and between the joint and the edge of the casting or strand moving through the mold cavity 1. Concerning this disclosure, reference is made to Handbuch des Stranggiessens (Manual of Continuous Casting), Hermann, pp 135-137.

I claim

1. Continuous casting mold assembly for metals and particularly for steel, comprising a plurality of mold plates angularly disposed relative to one another and forming a longitudinally extending laterally closed mold cavity, first means connected to said mold plates for oscillating each said mold plate in the radial direction of the mold cavity, second means connected to each said mold plate at a location spaced from the connection of said first means thereto for oscillating each said mold plate in the plane of its surface within the mold cavity, each of said mold plates having one longitudinally extending edge in abutment with the surface

of another said wall plate which lines the mold cavity, said abutting edge having a groove formed therein extending in the longitudinal direction of the mold cavity, the groove being spaced outwardly from the surface of said wall plate defining the mold cavity, a packing strip positioned within and extending in a longitudinal direction of the groove, and means for applying a pressurized heat-resistant lubricant into the groove for forcing said packing strip in sealing action between the abutting said mold plates for preventing any outward flow of the molten metal within the mold cavity.

5 2. Continuous casting mold assembly, as set forth in claim 1, characterized therein by a frame laterally enclosing and spaced outwardly from said mold plates, said frame extending in the longitudinal direction of the mold cavity, adjustable abutment strips extending transversely of the longitudinal direction of the mold cavity and extending between said mold plates and said frame.

15 3. Continuous casting mold assembly, as set forth in claim 1, characterized in that said second means for oscillating each said mold plate comprises an oscillating device in contact with one longitudinally extending edge of each said mold plate.

20 4. Continuous casting mold assembly, as set forth in claim 2, characterized in that a plurality of elastic elements are associated with each said mold plate and said elastic elements extend transversely of the longitudinal direction of the mold cavity and are connected to and extend between said frame and said mold plates.

25 5. Continuous casting mold assembly, as set forth in claim 4, characterized in that said elastic elements are articulated to said mold plates and said frame.

30 6. Continuous casting mold assembly, as set forth in claim 4, characterized in that said elastic elements are adjustable in length relative to their position in the longitudinal direction of the mold cavity for adapting to the tapering configuration of the casting as it solidifies while passing through the mold cavity.

35 7. Continuous casting mold assembly, as set forth in claim 1, characterized in that rolls are mounted at the lower ends of each of said mold plates for supporting said mold plates.

40 8. Continuous casting mold assembly, as set forth in claim 1, characterized in that said mold plates are disposed perpendicularly to one another forming a rectangular cross-section for the mold cavity transversely of the longitudinal direction thereof.

45 9. Continuous casting mold assembly, as set forth in claim 1, characterized in that said first means for oscillating said mold plates comprises an oscillating generator mounted on each of said mold plates in spaced relationship from the edges thereof.

50 10. Continuous casting mold assembly, as set forth in claim 1, characterized in that said first means for oscillating said mold plates comprises an oscillating device connected to the exterior surface of each said mold plate in spaced relationship from the edges thereof for oscillating said mold plates in the radial direction of the mold cavity.

55 11. Continuous casting mold assembly, as set forth in claim 8, characterized in that each said mold plate extends between two oppositely spaced said mold plates and has one edge extending in the longitudinal direction of the mold cavity in contact with the surface of one of the oppositely spaced said mold plates which defines the mold cavity and with its other edge extending in the longitudinal direction of the mold cavity extending outwardly from the surface of the other one of said oppositely spaced said mold plates which forms the opposite surface of the mold cavity, and said second means for oscillating said mold plates connected to the other edge of each said mold plate.
